US00D633388S

(12) United States Design Patent
Andre et al.

(10) Patent No.: US D633,388 S
(45) Date of Patent:  Mar. 1, 2011

(54) PACKAGING

(75) Inventors: Bartley K. Andre, Menlo Park, CA (US); Daniel J. Coster, San Francisco, CA (US); Daniele De Iuliis, San Francisco, CA (US); Richard P. Howarth, San Francisco, CA (US); Jonathan P. Ive, San Francisco, CA (US); Steve Jobs, Palo Alto, CA (US); Duncan Robert Kerr, San Francisco, CA (US); Shin Nishibori, Portola Valley, CA (US); Matthew Dean Rohrbach, San Francisco, CA (US); Peter Russell-Clarke, San Francisco, CA (US); Douglas B. Satzger, Menlo Park, CA (US); Calvin Q. Seid, Palo Alto, CA (US); Vincent Keane Seid, legal representative, Los Gatos, CA (US); Christopher J. Stringer, Woodside, CA (US); Eugene Antony Whang, San Francisco, CA (US); Rico Zorkendorfer, San Francisco, CA (US)

(73) Assignee: Apple Inc., Cupertino, CA (US)

() Term: 14 Years

(21) Appl. No.: 29/363,450

(22) Filed: Jun. 9, 2010

Related U.S. Application Data

(60) Continuation of application No. 29/340,508, filed on Jul. 20, 2009, now Pat. No. Des. 620,795, which is a division of application No. 29/281,505, filed on Jun. 25, 2007, now Pat. No. Des. 596,485.

(57) CLAIM

The ornamental design for packaging, as shown and described.

DESCRIPTION

FIG. 1 is a top perspective view of packaging showing our new design;

FIG. 2 is a bottom perspective view thereof;

FIG. 3 is a front view thereof;

FIG. 4 is a rear view thereof;

FIG. 5 is a side view thereof;

FIG. 6 is another side view thereof;

FIG. 7 is a top plan view thereof; and,

FIG. 8 is a bottom plan view thereof.
